ATTORNEY.

UNITED STATES PATENT OFFICE.

BENJAMIN F. ZELL, OF ORRVILLE, OHIO, ASSIGNOR OF ONE-HALF TO
ADAM FOGEL, OF SAME PLACE.

CULTIVATOR.

SPECIFICATION forming part of Letters Patent No. 434,747, dated August 19, 1890.

Application filed June 5, 1890. Serial No. 354,410. (No model.)

To all whom it may concern:

Be it known that I, BENJAMIN F. ZELL, a citizen of the United States, and a resident of Orrville, county of Wayne, State of Ohio, have invented a new and useful Improvement 5 in Cultivators, of which the following is a full, clear, and exact description, reference being had to the accompanying drawings, making part of this specification.

10 My invention relates to improvements in cultivators, and more particularly to that class of cultivators designated as riding or sulky cultivators, the object of which is to provide a strong and rigid support for the 15 operator, to which all of the operative parts are adjustably secured within reach of the operator.

With these ends in view my invention consists in certain features of construction and 20 combination of parts, as will be hereinafter described, and pointed out in the claims.

Figure 1 of the accompanying drawings is a view in perspective of a cultivator illustrating 25 my invention. Fig. 2 is a side view of a portion of detail.

Similar letters of reference indicate corresponding parts in both the figures of the drawings.

A represents an inverted-U-shaped axle-frame; B, a bifurcated pole, the rear end of which is secured to the main axle; C, an inverted-U-shaped front frame-piece, which serves as a support for the pole B and gang frame or beam D, the side bars E connecting 30 the main axle with the frame-piece C. The axle-spindle F has a pivotal connection with axle-frame, as shown at a, the axis of said pivot being vertical. On the inner end of said spindle is provided a toothed segment 35 a', engaging a pinion a'', having corresponding teeth. Said pinion is mounted on the lower end portion of a vertical shaft a''. On the upper end portion of said shaft is provided an outwardly-projected arm a''. As will be 40 seen, these parts are used in duplicate. The arms a'' are pivotally secured together by a coupling-link a''.

At the top of the axle-frame A is provided a toothed quadrant a'', to which is pivotally 45 secured a hand lock-lever a'', one end of which

is pivoted to the link a'', as shown at a''. The other end of the lever is provided with a spring-actuated bolt a'', said bolt adapted to engage the teeth a'' of the quadrant a''.

The gang frame or beam D is formed of 55 bars of iron, and is of the form shown. The front end of the frame is pivotally secured to a clip b, which is supported by and rotates about the horizontal portion of the frame-piece C.

To adjust the front end of the gang-frame on the frame C, a number of short sleeves, as b', are provided, which may be placed on either side of the clip in such numbers or divisions as to place the clip in the desired 65 line of lead for the gang.

To raise or lower the gang-frame or to lock it at any desired elevation, a quadrant b'' is secured to the axle-frame, to which is pivotally secured a lock-lever b'', having one of its 70 ends connected by a lifting-rod b'' to the gang-frame D.

The gang frame or beam D is formed of a continuous bar extending from the frame-piece C to the rear portion of the wheels H, 75 said bar being bent in a zigzag form to properly place the plows—that is, bent from alignment from z to y, from y to x, from x to w, and from w to v, to which the plow-standards are secured in the usual way, a brace or girder 80 portion u extending from x to z.

The plows are secured to the standards o by an open clip b'', through the lips of which is passed a tightening-bolt b''. By slackening the bolt the clip may be moved up or down 85 on the standard and secured in desired adjustment by tightening said bolt, or turned obliquely to the line of draft. The blade b'' may be secured to the clip by rivets or screws.

On the rods b'' a distance from the lower 90 end is provided a collar b'', below which is placed a coil-spring b'', the lower end of which rests on a perforated plate d, secured to the gang-frame. The spring serving as a cushion to all of the plows, in the event of a plow 95 striking an obstruction the spring will yield to the pressure, the lower end of the rod b'' passing down through the plate d and between the bars forming the gang-frame.

To secure the corn-shield J to the gang- 100

frame, a spring-carrier L is provided, having one of its ends d' secured to the frame, a coil d^2 at its central portion, and its free end d^3 secured to the shield, by which arrangement 5 the shield may rise and fall independently of the frame D.

In operation the driver is seated on the seat K, his feet resting on the supports d^4 , to raise or lower the gang-frame and plows, and to fix 10 them in desired adjustment he will move the hand-lever b^3 about its pivotal connection with the quadrant b^2 , the locking-bolt to engage the teeth at the desired point, and to turn the wheels H to travel obliquely to the 15 line of draft for the purpose of holding the plows to the corn on hillsides, or to keep the machine from sliding bodily down when used on sloping ground, the lock-lever a^{10} is moved about at its pivotal connection with the quadrant a^6 , the link a^5 , with the arms a^4 , vibrated, 20 rotating the shafts a^3 and pinions a^2 , said pinions engaging the segment a' , by which movement the spindle F is vibrated about its pivotal connection a with the frame A. 25 The convenience and ease with which the several parts may be operated to adapt them to the condition of the ground and the crop to be cultivated will be apparent to all persons familiar with the use of such machines. 30 Having thus fully explained the nature and object of my invention, what I claim as new, and desire to secure by Letters Patent, is—

1. The combination, in a cultivator, of the inverted-U-shaped axle-frame A, the divided 35 tongue B, the inverted-U-shaped frame-piece

C, side bars E, spindles F, pivotally secured to the axle-frame to swing obliquely to the line of the draft, said spindles having a toothed segment a' on the inner end thereof to engage a pinion a^2 , mounted on a vertical 40 shaft a^3 , journaled to said axle-frame, and having at their upper ends arms a^4 , pivotally secured together by a link a^5 , a toothed quadrant a^6 , and an actuating lock-lever b^3 , by which the spindles may be rotated about their 45 pivotal connection with the axle-frame to turn the carrying-wheel H obliquely to the line of draft, substantially as described, and for the purpose set forth.

2. The combination of the inverted-U-shaped axle-frame, the spindles F, pivotally secured thereto, and the described means for rotating said spindles about their pivotal connection with said frame, the segment b^2 , lock-lever b^3 , lifting-rod b^4 , spring b^9 , and gang-frame D, substantially as described, and for the purpose set forth.

3. The combination, with a cultivator as hereinbefore described, of a gang-frame of the form substantially as herein shown and 60 described, standards o , secured thereto, blades b^7 , secured to said standards by the open clips b^6 , the clip b , and the sleeves b' , substantially as described, and for the purpose set forth.

In testimony whereof I have hereunto set 65 my hand this 31st day of May, A. D. 1890.

BENJAMIN F. ZELL.
